UNITED STATES PATENT OFFICE

103,537

DESIGN FOR A FLASHLIGHT CASING

Onnie Mankki, Cleveland Heights, Ohio, assignor to The Bridgeport Metal Goods Manufacturing Company, Bridgeport, Conn., a corporation of Connecticut

Application January 12, 1937, Serial No. 67,015

Term of patent 14 years

To all whom it may concern:

Be it known that I, Onnie Mankki, a citizen of the United States, residing at 3373 Tullamore Road, Cleveland Heights, county of Cuyahoga, State of Ohio, have invented a new, original, and ornamental Design for a Flashlight Casing, of which the following is a specification, reference being had to the accompanying drawing, forming part thereof.

Fig. 1 is a side elevation of a flashlight casing, showing my new design;

Fig. 2 is a plan view thereof; and

Fig. 3 is an end view looking from the left of Figs. 1 and 2.

I claim:

The ornamental design for a flashlight casing, substantially as shown.

ONNIE MANKKI.
